GROUND EFFECT MACHINE

Ernst J. De Ridder, Henrico County, Va., assignor to
Reynolds Metals Company, Richmond, Va., a corpora-
tion of Delaware

Filed July 27, 1960, Ser. No. 45,647

8 Claims. (Cl. 180—7)

This invention relates to ground effect machine or vehicle of the character which has a superatmospheric pressure air cushion between a lifting area and a co-operating ground surface.

According to this invention an air cushion with superatmospheric air pressure is produced below the lifting area of the machine and above the cooperating ground surface. Such air cushion has an open periphery to the atmosphere between the lifting area and the ground surface. The lifting power of this ground effect machine or vehicle is enhanced by the provision of effective means for maintaining a large proportion of the superatmospheric pressure air of the air cushion within the surrounding periphery and in a manner to prevent undue loss of superatmospheric air from the air cushion outwardly to the atmosphere along such periphery.

The means for producing the air cushion may include a relatively slow speed, low pressure jet which is downwardly and inwardly directed at a relatively large angle to a horizontal plane along the periphery. A relatively high pressure, high speed jet is provided outside of, and adjacent to, the low pressure jet, and the high pressure jet is downwardly and inwardly directed at a relatively smaller angle, or sharper angle, to such horizontal plane. By this construction the high pressure jet produces an effective barrier or seal around the air cushion and greatly reduces any outward loss of superatmospheric pressure air from the air cushion to the surrounding atmosphere. By this construction the lifting power of the machine is greatly increased, and is maintained at a high standard of operation.

A low pressure air supply means, such as a low pressure fan, supplies air at relatively low pressure to the low pressure jet and a high pressure air supply means, such as a high pressure fan, supplies air to the relatively high pressure high speed jet. The effectiveness of this combination is enhanced, when desired, by having the high pressure air supply means or fan obtain its air supply from the low pressure air supply means or fan.

More specifically, the low pressure air fan receives air at atmospheric pressure and supplies low pressure air to a low pressure plenum chamber, and the plenum chamber supplies low pressure air to the low pressure air jet. A high pressure air fan receives air from the low pressure plenum chamber and supplies high pressure air to a high pressure plenum chamber which supplies high pressure air to the high pressure air jet.

In an embodiment of this invention the air fans are aligned on a common shaft. If desired, the common shaft is in the vertical position. In another embodiment, the fans are aligned on a common shaft which is horizontal.

Accordingly, it is an object of this invention to provide a ground effect machine or vehicle having one or more of the features herein disclosed.

Another object of this invention is to provide a method of lifting a ground effect machine, which method has one or more of the features herein disclosed.

Other objects are apparent from this description, and/or the accompanying drawings, in which:

FIGURE 1 is a diagrammatic vertical cross-section of an embodiment of this invention.

FIGURE 2 is a vertical cross-section of a portion of an embodiment somewhat similar to FIGURE 1, with the jet constructions slightly modified.

2

FIGURE 3 is a vertical cross-section of another embodiment of this invention, taken along line 3—3 of FIGURE 4.

FIGURE 4 is a cross-section along the line 4—4 of FIGURE 3.

In FIGURE 1, a ground effect machine or vehicle is generally designated by the numeral 10. The machine or vehicle has an air lifting area along its under surface 12 which is above a cooperating ground surface indicated by the line 14. An air cushion 16 of super-atmospheric pressure air is produced below the lifting area 12 and above the ground surface 14. The air cushion 16 has an open periphery which is open to the atmosphere between the area 12 and the ground surface 14. This periphery is indicated, in general, by the vertical lines 18 and 20. These lines diagrammatically indicate a periphery or peripheral zone which extends completely around the general lifting perimeter of the machine 10.

Means for producing the air cushion 16 may include a relatively slow speed, low pressure jet 22 which is downwardly and inwardly directed at a relatively large angle 22a to a horizontal plane, such as the plane of the ground surface 14.

The means for maintaining the air cushion may also include a relatively high pressure, high speed jet 24 which is downwardly and inwardly directed at a relatively smaller, or sharper, angle 24a to the horizontal plane, which may be the ground surface 14.

The words "ground surface" are intended to describe any suitably cooperating surface underneath the vehicle. Such ground surface may be actual ground, such as a road, a field, and the like. Alternatively, the ground surface need not be ground in the ordinary sense of the word, but may also include liquid surfaces, such as swamps, rivers, lakes, oceans, and the like. The ground surface may also be a combination of water and ground, such as where water and ground merge together along a shore line or along a very shallow surface of water.

A low pressure air supply means is generally indicated by the numeral 26 and this may be in the form of a low pressure fan 28 which receives atmospheric air from the atmosphere 30 adjacent to the vehicle, and forces such air at relatively low pressure along the plenum chamber 32 to the low pressure jet 22. Such relatively low pressure air is at superatmospheric air pressure, however.

A high pressure supply means, or fan 34, supplies air at relatively high pressure, along the high pressure plenum chamber construction 36, 38 to supply air at relatively high pressure to the high speed jet 24. The radial tubes 36 receive the air from fan 34 and discharge it into annular chamber 38. The high pressure air supply means or fan 34 obtains its air supply preferably from the low pressure air supply means 28, through the inlet 36', which is located in the low pressure plenum chamber 32. The relatively high pressure air is also at superatmospheric air pressure.

For example, the high pressure fan 34 may pick up only from $\frac{1}{5}$ to $\frac{1}{2}$ of the air volume furnished by the low pressure fan 28, to supply the high pressure jet 24.

The peripheral jet 24 of the higher air pressure has a much smaller opening than the peripheral jet 22 of the low pressure construction, to produce the higher air speed of jet 24.

The outside higher air speed of the jet stream produces a high pressure, relatively fast air curtain 40 which has a much higher air speed than can be produced by the low pressure plenum chamber 32 which supplies low pressure air to the inner peripheral low pressure jet 22. Consequently, the jet 22 produces a relatively slow air stream.

The slower air speed of the jet stream from low pres-

sure jet 22 produces a low pressure, relatively slow, air curtain 42 surrounding the air cushion 16.

Since the air flow of the high pressure speed jet stream or curtain 40 cannot be deviated as easily as a low pressure low speed jet stream 42, a very efficient sealing action is produced around the air cushion 16, which maintains a large proportion of the superatmospheric pressure air of the air cushion 16 within the surrounding periphery 18, 20.

Referring to FIGURE 2, the relatively high pressure, high speed jet 50 has a smaller or sharper angle 52 with respect to a horizontal plane 54 than the angle 58 of the relatively low speed, low pressure jet 60.

The outside high pressure jet air stream or curtain 62 has a considerably higher speed than the low pressure, slow speed air stream or curtain 64. When the curtains 62 and 64 touch together an inwardly turning turbulence is created adding somewhat to the sealing effect around the air cushion 65.

To cut down the speed of the air flow in the area between the inner jet stream 64 and the outer jet stream 62, the vehicle bottom can be curved as shown at 66. This curvature 66 improves the sealing property of the high speed outer jet stream or curtain 62.

If desired, the outlet of the outer jet 50 may be located in a lower plane than the outlet of the low pressure jet 60. This also produces a beneficial sealing effect.

The high pressure jet 50 may be supplied from a high pressure plenum chamber 68, which may correspond to the high pressure plenum chamber 36-38 of FIGURE 1. The low pressure jet 60 may be supplied with low pressure air from the low pressure plenum chamber 70, which may be supplied with low pressure air in a manner similar to that shown in connection with low pressure plenum chamber 32 of FIGURE 1.

FIGURE 1 shows the fans 28 and 34 aligned on a common shaft 72 which is substantially vertical. The shaft 72 may be driven by any suitable means, not shown, such as an internal combustion engine, electric motor, and the like, which may be directly connected to the shaft 72. Alternatively, the driving means may be connected to the shaft 72 by any suitable transmission, such as a belt drive, gear and shaft drive, flexible shaft drive, and the like. The driving means may be placed either in one of the plenum chambers, or on the surface or platform 74. If desired, the engine may be a vertical shaft engine with a drive shaft aligned with and connected to the shaft 72 and spaced above the inlet 76 of the fan 28, so that the atmospheric air may enter the fan 28 through an annular space between the internal combustion engine and the air inlet 76. The internal combustion engine or motor may be in the plenum chamber 32 and may be connected by a belt drive or shaft drive with the shaft 72. The engine or motor may be in the plenum chamber 36, 38, if desired. Any other type of connection may be used, if desired.

FIGURES 3 and 4 show a construction in which the fans are connected to a horizontal shaft, and in which the driving means or engine is drivingly connected to such horizontal shaft.

In the embodiment of FIGURES 3 and 4 a ground effect machine 80 has a lifting area produced by the lower lifting surface 82 of the machine. The lifting area 82 cooperates with the ground surface 84, which may be the surface of ground, swamp, river, lake or ocean and the like or any combination thereof. An air cushion 86 is produced below the area 82 and above the ground surface 84, such air cushion being of superatmospheric air pressure. The cushion 86 has an open periphery surrounding the area 86, and is indicated by the dotted lines 87.

Means are provided to maintain the air cushion 86 at superatmospheric pressure, and such means may include a low pressure jet 92 which is downwardly and inwardly directed at a relatively large angle 92a to a horizontal

plane 94. The jet 92 extends along the open periphery 87 of the air cushion 86.

The low pressure jet 92 produces a peripheral, slow speed, air stream or curtain 88 or 90 which surrounds the air cushion 86.

A relatively high pressure, high speed, jet 96 is downwardly and inwardly directed at a relatively smaller or sharper angle 96a with respect to the horizontal plane 94. The jet 96 produces an air stream or curtain 98 of relatively high speed compared to the slow speed air stream or curtain 88, 90, which is produced by the jet 92. This produces a sealing zone 100 which holds a large proportion of the low pressure, superatmospheric air within the air cushion 86, and increases the lifting power of the ground effect machine 80.

A relatively low pressure air supply means or plenum chamber 101, 102 supplies low superatmospheric pressure air to the low pressure jet 92. The low pressure supply or plenum 101, 102 is supplied with air at relatively low pressure by the low pressure fan 104, which receives atmospheric air from the surrounding atmosphere 106, through the inlet 108, and discharges this atmospheric air at a relatively low superatmospheric air pressure into the plenum passageway 101 and through the passageway 108 to the low pressure plenum passageway 102.

A high pressure air supply means or plenum chamber 110, 112, and 114 supplies superatmospheric pressure air at relatively high pressure to the high pressure jet 96. The high pressure air supply means 110, 112 and 114 receives air from the low pressure air supply means 101 through the intake 116 of the high pressure fan 118. The high pressure fan 118 discharges into the connected horizontal passageways 110, 112 and 114, so that the high pressure air is discharged into the high pressure jet 96.

The construction is such that the slow speed, low pressure air curtain 88, 90 of the low pressure jet 92, which extends completely around the periphery 87 of the air cushion 86 produces a relatively low superatmospheric air pressure in the air cushion 86. The high pressure peripheral jet 96 produces a high pressure, high speed curtain 98, which confines the superatmospheric air in the air cushion by the confining zone 100 and tends to prevent outward discharge of the cushion air along the open periphery 87 into the atmosphere. The relationship of the jet 96 to the jet 92 is substantially the same as the previously described relationship of the jet 24 to the jet 22. Accordingly, a detailed description thereof is not repeated.

The fans 104 and 118 are drivingly connected to the horizontal shaft 120, 122, which in turn is connected to the source of power, such as the internal combustion engine 124. Alternatively, the shaft 120, 122 may be connected to any other source of power, such as an electric motor and the like.

If desired, the space 126, in which the engine 124 or the like is located, may be at the pressure of the atmosphere 106, and may be connected thereto if desired. Alternatively, the space 124 may have a pressure substantially the same as the pressure in the low pressure plenum 101, 102, in which case such space 126 may be connected by a suitable passageway, not shown, with such plenum 101, 102. Alternatively, the space 126 may be a high pressure space of substantially the same pressure as the high pressure plenum 110, 112, and 114, in which case such space 126 may be connected, by a suitable opening or openings, not shown, to the high pressure plenum 110, 112, and 114.

The engine 124 may exhaust into the space 126, or it may be provided with discharge or exhaust pipe, not shown, which passes through the wall of the vehicle 80 into the outer atmosphere 106 at any desired point.

The embodiments of this invention may be steered by any suitable means, such as by rudders, shifting weights, louvres, additional fans which may be turned in any desired direction, etc., as desired.

In the operation of the embodiments of the invention herein specifically disclosed, atmospheric air from the surrounding atmosphere 30 or 106 is raised to a relatively low superatmospheric pressure by the fans 28 or 104 and is discharged into the relatively low pressure plenum chambers 32 or 70, or 101, 102. Part of this relatively low superatmospheric pressure air is delivered to the low pressure jets 22, 60 or 92. Another part of this low pressure air is delivered to the intakes 36 or 116 of the high pressure fans 34 or 118, where such air is raised to a relatively high, superatmospheric air pressure and is discharged to the high pressure plenum chambers 36, 38, or 68, or 110, 112, 114. These high pressure plenum chambers respectively deliver high pressure air to the high pressure jets 24, 50, or 96.

The low pressure jets 22, 60 and 92 respectively produce low superatmospheric pressure, relatively slow air curtains 42, 64, or 88, 90, which respectively surround the relatively low superatmospheric pressure air cushions 16, 63 or 86. The high pressure jets 24, 50 and 96 respectively produce high pressure, relatively fast air curtains 40, 62 or 98, which are adjacent to and surround the slow air curtains 42, 64 and 88, 90.

The high speed curtains 40, 62 or 98 confine the respective slow speed curtains 42, 64 and 88, 90, and the respective air cushions 16, 63 and 86 to reduce materially the outward flow of superatmospheric air from the respective air cushions, past their respective open peripheries to the surrounding atmosphere.

This action materially increases the lifting powers of the lifting areas of the respective ground effect machines disclosed.

Hence a relatively simple and efficient ground effect machine construction has been provided by this invention.

While the form of the invention now preferred has been disclosed as required by the statutes, other forms may be used, all coming within the scope of the claims which follow.

What is claimed is:

1. In combination: a ground effect machine having a lifting area above a cooperating ground surface to define an air cushion between said area and surface; a downwardly directed relatively low pressure annular air jet along the periphery of said air cushion directed downwardly at a relatively large angle to a horizontal plane; a downwardly and inwardly directed relatively high pressure annular jet around said low pressure air jet at a relatively small angle to said horizontal plane to aid in sealing said air cushion under said lifting area; a low pressure air fan receiving air at atmospheric pressure and supplying low pressure air to a low pressure plenum

chamber, said low pressure plenum chamber supplying said low pressure air to said low pressure air jet; and a high pressure air fan receiving air from said low pressure plenum chamber and supplying high pressure air to said high pressure air jet.

2. A combination according to claim 1 in which said fans are aligned on a common shaft.

3. A combination according to claim 1 in which said fans are aligned on a common shaft and in which said shaft is vertical.

4. A combination according to claim 1 in which said fans are aligned on a common shaft and in which said shaft is horizontal.

5. In combination: a ground effect machine having a lifting area above a cooperating ground surface to define an air cushion between said area and surface; a downwardly directed relatively low pressure air jet along the periphery of said air cushion directed downwardly at a relatively large angle to a horizontal plane; means supplying relatively low pressure air to said low pressure jet; a downwardly and inwardly directed relatively high pressure air jet around said low pressure air jet at a relatively small angle to said horizontal plane to aid in sealing said air cushion under said lifting area; and means supplying relatively high pressure air to said high pressure jet; said means supplying low pressure air to said low pressure jet comprising a low pressure air fan receiving air at atmospheric pressure and supplying low pressure air to a low pressure plenum chamber, which chamber supplies low pressure air to said low pressure air jet; said means supplying high pressure air to said high pressure jet comprising a high pressure air fan receiving air from said low pressure plenum chamber and supplying high pressure air to said high pressure air jet.

6. A combination according to claim 5 in which said fans are aligned on a common shaft.

7. A combination according to claim 5 in which said fans are aligned on a common shaft and in which said shaft is vertical.

8. A combination according to claim 5 in which said fans are aligned on a common shaft and in which said shaft is horizontal.
